UNITED STATES PATENT OFFICE.

ELMER L. VISE AND CHARLES DENHAM, OF WEST TERRE HAUTE, INDIANA.

COAL-DISTRIBUTER.

1,038,241.

Specification of Letters Patent. Patented Sept. 10, 1912.

Application filed March 23, 1912. Serial No. 685,775.

To all whom it may concern:

Be it known that we, ELMER L. VISE and CHARLES DENHAM, citizens of the United States, residing at West Terre Haute, in 5 the county of Vigo and State of Indiana, have invented an Improved Coal-Distributer, of which the following is a specification.

Our invention relates to an apparatus whereby coal is discharged from a primary 10 distributor upon another which is in the nature of a chute adapted to deliver different grades of coal to different receptacles, especially cars for transportation.

The details of construction, arrangement, 15 and operation of parts are as hereinafter described, and illustrated in the accompanying drawings, in which—

Figure 1 is a side elevation of the entire apparatus. Fig. 2 is a perspective view of 20 the first or primary distributing chute. Fig. 3 is a plan view of the main coal distributing chute, as viewed in perspective. Fig. 4 is a perspective view of one of the pivoted gates arranged and locked in alinement with 25 one of the fixed sectional partitions. Fig. 5 is a diagrammatic plan view of a portion of the distributing chute or platform showing the arrangement of the fixed angular and longitudinal sectional partitions.

30 The working parts of the apparatus are arranged in and supported by a frame comprising vertical posts 1 and inclined top bars 2. The first distributing chute A has a trough-like form and is constructed of sheet 35 metal and with lateral flanges which rest on and are secured to the aforesaid bars 2 of the frame. Directly below this chute and inclined at a greater angle, is the main distributing chute B. The body of the chute A 40 has four segmental partitions 3, 4, 5, and 6, the same being arranged transversely and just below four openings 7, 8, 9, and 10 from which are pendent four spouts 11, 12, 13, and 14 that serve for the discharge of coal 45 upon the distributing chute or platform B. The lower end of the chute is provided with a hood and spout 15 which is arranged in a pendent position and slightly inclined backward, so as to deliver upon a particular portion 50 of the main distributing chute B, as will be further explained. The upper end of the chute A is closed by a bulkhead 16 and pro-

vided with a platform 17 having side boards 18, the latter converging slightly, so as to direct a stream of coal into a cylindrical 55 screen α , which is indicated by dotted lines in Fig. 1, but forms no part of our present invention.

Mine-cars filled with coal are hoisted by a tipple and discharge coal upon the platform 17, whence it is directed by gravity into a cylindrical screen α . The revolution of the screen agitates the coal, and fine or slack coal drops through the smaller mesh of the screen; the coal of next coarser grade, known 60 as "nut", falls through the next screen section; the third grade or size of coal, known as "egg", falls through the succeeding screen section; the next largest grade of coal, known as "four-inch lump", falls through 65 the last section or largest mesh of the screen; and the largest size of all, known as "domestic", passes out of the lower open end of the cylinder. These different grades or sizes of coal fall downward into the several 70 compartments of the chute which are provided with the openings 7, 8, 9, and 10, and thence descend through the spouts 11, 12, 13, and 14, correspondingly, and are delivered into compartments in the distributing 75 chute B, as will be further described. The coal which passes over the lower end of the chute A and through the inclined hood and spout 15 is deposited in the lower compartment of the distributing chute B. The platform or floor of the distributing chute B is 80 covered with sheet metal, so that it is smooth and durable.

As shown in Fig. 3, the platform is elongated and provided with parallel outer sides 85 19 and three intervening, sectional partitions 20, 21, and 22 which are also arranged longitudinally parallel and serve to form longitudinal coal chutes or passages 23, 24, and 25, all of which open at the lower end of the 90 platform B. The alined sections of the partitions 20, 21, and 22 are separated by narrow spaces, and, in the case of the two partitions 20 and 22, the gateways or openings 95 are closed by hinged gates. In the case of 100 the sectional partition 20, the gateways are provided with gates 26, 26^a, 27^a, and 28^a, and in the case of the other sectional partition 22 the gateways are provided with gates

29, 29^a, 30^a, and 31^a. Each of the gates named is pivoted at 32 and is thus adapted to be swung laterally, as indicated by dotted lines, and may be locked in different positions as will be presently described.

In the wide space provided between the sectional partitions 21 and 22, there is arranged a series of fixed partitions which are located at a right angle to each other and spaced 10 apart in the length of the platform, so as to practically divide the space in which they are located into five hoppers, or receiving compartments, indicated by letters *a*, *b*, *c*, *d*, and *e*. Each of the partitions has a long 15 and short side indicated respectively, by numerals 33 and 33^a. The lower end of each long side 33 abuts the longitudinal sectional partition 21 and each of the short sides 33^a is provided with a latch or locking device 20 34 which is adapted to engage in one of the gates 29, 29^a, etc. A long gate is pivoted at the apex 35 of the angle of the fixed partitions 33, 33^a, and is adapted to swing laterally, as shown by full and dotted lines. 25 These gates are indicated by numerals 36, 36^a, 36^b, and 36^c.

In the chute or coal passage formed between the adjacent partitions 20 and 21, there is formed a series of openings or scut- 30 tles 37, 37^a, 37^b, and 37^c, that serve for downward passage of coal into and through spouts 38, 38^a, 38^b, and 38^c, these several spouts serving to deliver into cars running on tracks laid beneath the distributing chute 35 B, as indicated in Fig. 1.

It will be understood that the different kinds or grades of coal delivered from the respective spouts 11, 12, 13, and 14 of the receiving chute A are deposited in the re- 40 spective compartments or hoppers of the distributing chute B, the same being indicated by *a*, *b*, *c*, *d*, and *e*. When the coal has been thus deposited in the respective compartments, it may be directed in various 45 downward courses into or through the several chutes or passages 23, 24, and 25, this being practicable by the manipulation of the pivoted gates before described. For example, in Fig. 3, the gates are adjusted to direct 50 slack coal from the upper compartment *a* into the side chute 25, which it will follow to the end of the chute and pass off the same. It will be seen that the gate 36 is, for this 55 purpose, adjusted to the left and that the short gate 29 is in alinement with the short fixed partition 33^a, thus leaving the passage-way from the compartment *a* to the chute 22 perfectly clear. On the other hand, nut coal delivered into the second compartment 60 *b* will pass therefrom into the left-hand chute 24 and thus into the opening or scuttle 37^a and down through the spout 38^a, this being effected by adjustment of the long gate 36^a to the right; again, egg coal delivered into the hopper or compartment *c* may

be directed downward into the next compartment below, *d*, and laterally through the chute or passage 24 and into the chute or passage 23 and thus off the end of the platform. For this purpose, it will be seen 70 that the short gate 27^a is adjusted in alinement with and locked to the sectional partition 22 and that the short gate 28^a of the sectional partition 20 is adjusted to the right. It will be seen that by this arrangement 75 the egg coal coming from compartment *c* will mingle with the lump coal deposited in compartment *d*, so that both together pass out across the chute 24 and into and out of the outside chute 23. The different grades 80 of coal may in this way be directed through the several spouts, 38, 38^a, etc., and off the lower end of the platform B into cars or other receptacles below any may be mixed 85 with each other, when desired.

What we claim is:—

1. The improved coal-distributing apparatus, comprising a primary distributing chute having a series of openings and spouts pendent therefrom and a main distributing 90 chute arranged beneath the first-named one and provided with compartments arranged directly under the several spouts of the upper distributor, the said compartments being in turn provided with openings and 95 pendent spouts for final delivery into cars or other receptacles, as described.

2. The improved coal distributing chute, comprising an inclined platform having, 100 a series of sectional longitudinal partitions, a series of fixed partitions composed of long and short sides arranged in the central space on the platform, long gates pivoted at the apex of the fixed partitions and adapted for adjustment right and left, and a series of 105 shorter gates adapted for adjustment in line with the shorter fixed partition and in line with the adjacent sectional longitudinal partition for directing coal from a compartment into the right hand chute or passage or from said compartment into the one next below, substantially as described.

3. The improved coal distributing chute, comprising an inclined platform having parallel sectional partitions between two of 115 which there is formed a series of scuttles having a corresponding series of spouts, fixed partitions arranged at an angle to each other and provided with swinging gates adapted for lateral adjustment for 120 directing coal from a compartment above the partition laterally into the longitudinal passage and thus to the scuttle, substantially as described.

4. The improved coal distributing chute, 125 comprising an inclined platform having parallel sides and three parallel sectional partitions which divide the platform into three longitudinal coal chutes or passages, one of which is provided with a series of scuttles, 130

the two outer sectional partitions having a series of swinging gates for closing the openings therein, a series of fixed partitions composed of long and short sides arranged at 5 an angle to each other in the wide space between two of the sectional partitions, a long gate pivoted at the apex of each angle of the fixed partitions, and short gates pivoted to the right hand sectional partition and adapt-

ed to close the openings therein or to swing 10 into alinement with the short fixed partition, substantially as described.
